UNITED STATES PATENT OFFICE.

EDWARD WESTON, OF NEWARK, NEW JERSEY, ASSIGNOR TO THE WESTON ELECTRIC LIGHT COMPANY, OF SAME PLACE.

DEVICE FOR EQUALIZING THE ARCS OF ELECTRIC LAMPS.

SPECIFICATION forming part of Letters Patent No. 240,211, dated April 12, 1881.

Application filed May 31, 1880. (No model.)

To all whom it may concern:

Be it known that I, EDWARD WESTON, of Newark, New Jersey, have invented an Improvement in Devices for Equalizing the Arcs 5 of Electric Lamps Operated in Series in the Same Circuit, of which the following is a specification.

My improvement, the object of which is to maintain uniform lengths of arc in a number 10 of electric lamps operated in the same circuit, relates to devices for effecting at equidistant intervals the bringing together of all the pairs of carbons in the circuit independently of the ordinary regulating devices contained in each 15 lamp; and my invention consists in the combination, with the main circuit, which includes the lamps and their regulators, of a resistance-circuit surrounding a circuit-breaker which, at prescribed intervals, suddenly varies 20 the resistance in the main circuit, and hence, for the instant, so varies the magnetic condition of the magnets in all the lamps that all the pairs of carbons are in an inappreciable length of time brought to their initial positions, and then immediately removed therefrom by the ordinary action of the regulators 25 in the several lamps, by which all the pairs of carbons are separated to like distances, respectively, and hence all the arcs are made 30 uniform in length. By this means any irregularity in the rate of combustion of the carbons in the different lamps is corrected before there is time for any considerable elongation of any one arc and consequent diminution 35 in the length of the other arcs.

My invention also embraces certain features relating to the construction of a circuit-breaker especially adapted for employment in this connection.

40 In the accompanying drawings and diagrams, which illustrate the construction of my circuit-breaker and the mode of employing it in a circuit containing several electric lamps, Figure 1 is a side elevation of my circuit-breaker and an arbitrary representation of the principal circuit, including a dynamo-electric machine and an electric lamp, and also a representation of a derived circuit containing a resistance-coil. Fig. 2 is a front elevation of 45 the circuit-breaker. Fig. 3 is a top view of the same. Fig. 4 is a transverse section through 50

the line xx on Fig. 1. Fig. 5 is a central longitudinal section through the line yy on Fig. 4. Fig. 6 is a diagram representing two electric lamps in the same circuit with my circuit-breaker and a dynamo-electric machine. 55

My circuit-breaker consists of a bed-plate, A, to which suitable vertical standards a , a' , and a'' are affixed for the support of the several parts. 60

The driving-shaft B of the circuit-breaker has its journal in the standard a , and is provided with a driving-pulley, B', by means of which it is constantly rotated by power derived from some outside source. 65

The inner end of the main shaft is provided with a slotted crank-disk, b, to which the adjustable crank-pin b' is affixed. This crank-pin forms the axis for the impelling-pawl C, the free end of which engages the teeth in the 70 ratchet-wheel c, and with each revolution of the main shaft turns the ratchet-wheel a greater or less distance, according to the degree of stroke which is given to the impelling-pawl by the adjustment of the crank-pin in the slotted crank-disk. The ratchet-wheel c is 75 loosely mounted upon the end of the counter-shaft D, which has its bearing in the standard a' .

The counter-shaft D, on one side of its bearing, is provided with a fixed collar, d, against which the loose ratchet-wheel c is placed. An arm, d' , projects radially from the collar d , and is caught by the stud c' , projecting laterally from the face of the ratchet-wheel c, as the latter turns. On the opposite side of its bearing the shaft D is provided with a radial arm, D', from the end of which there projects laterally a slotted stud, D'', in which is inserted a brush, D³, composed of thin strips of sheet metal. 80 The counter-shaft D is free to turn in its bearings, and the tendency of gravity is to keep it in the position where the brush-holder D'' hangs downward, and it remains in that position until the arm d' is caught by the stud c' as the 85 ratchet-wheel c rotates. By the engagement of the stud c' with the arm d' the brush-holder is carried upward, and continues to move around with the ratchet-wheel c until it has been carried over the center on the top, when it is free 90 to respond to the action of gravity and drops suddenly. 95 100

The standard a' is provided with a binding-screw, E, to which one end of the line-wire or main circuit is affixed, and the brush D³ is therefore in constant electrical connection with the machine which supplies the current, which in Fig. 1 is arbitrarily represented by the letter M. The brush D³ bears upon the stationary cylinder F, a portion, f, of the periphery of which is formed of wood or some other non-conductor, while the rest of the periphery is metal, and is electrically connected with the standard a^2 , to which the opposite end of the line-wire or main circuit is connected. It will thus be seen that the main circuit is broken whenever the brush D³ is drawn over that part of the cylinder F which is made of wood. The result is that the carbons of the lamp (arbitrarily represented by the letter L in Fig. 1) are, at the instant when the break takes place, brought together by the sudden weakening of the attractive force of the electro-magnet in the lamp, which had theretofore held them apart. They are no sooner brought together, however, than they are separated, because the break in the main circuit is immediately closed by the renewed contact of the brush D³ with the metallic part of the cylinder F. The cylinder F is made adjustable upon its axis, so that the wood f in its periphery may be adjusted to a higher or lower position on that side of the cylinder which the brush D³ bears upon in its fall from its highest to its lowest position. If the brush D³, during the first part of its falling movement, is drawn over the wood f, the duration of the break in the circuit will be greater than it is when the cylinder F is so turned that the brush D³ is drawn over the wood f during the latter part of its falling movement. By this means of adjustment I am enabled to vary the duration of the break in the circuit, and hence regulate its duration with reference to the extent to which it is necessary to weaken the force of the magnets in the lamp or lamps. The instant the brush D³, after having been drawn over the wood f, renews its contact with the metallic part of the cylinder F the full strength of the current is returned into the main circuit, restoring the attractive force of the electro-magnets in the lamps, and thus causing them to perform their functions of separating the carbons to the prescribed distances.

I connect the two standards a' and a^2 , respectively, with the opposite ends, g and g' , of a derived circuit containing the resistance-coil G, in order to prevent the extinction of the light when the circuit is broken. This mode

of operation may be employed usefully in governing the combustion of the carbons in all kinds of lamps. In Fig. 1 I have shown it in connection with a gravity-lamp, in which the weight tending to diminish the distance between the points of the carbons is counterbalanced by the attractive force of an electro-magnet constructed in accordance with the description contained in my application for a patent filed July 8, 1879.

Fig. 6, which contains arbitrary representations of two electric lamps, H and I, shows the method of employing my circuit-breaker (indicated arbitrarily by the letters C B) for governing the lengths of the arc in several lamps operated in the same circuit from a single dynamo-electric machine, (indicated arbitrarily by the letter M.)

I claim as my invention—

1. An electric circuit including one or more electric lamps and a circuit-breaker, in combination with a resistance-circuit the ends of which are respectively connected with the main circuit on opposite sides of the circuit-breaker, whereby the resistance-circuit affords a path for the current parallel with the path afforded by that part of the main circuit which includes the circuit-breaker, substantially as and for the purpose set forth.

2. The combination, in an electric circuit, of one or more electric lamps having magnetic regulators with a continuously-operating periodic circuit-breaker, substantially as and for the purpose set forth.

3. The combination, in an electric circuit, of one or more electric lamps having magnetic regulators with a circuit-breaker consisting of the metallic cylinder F, having the gap f in its periphery, and being electrically connected with one end of a break in the main circuit, and the revolving brush D³, electrically connected with the other end of the break in the main circuit, substantially as and for the purpose set forth.

4. In a circuit-breaker substantially such as described, the adjustable cylinder F, in combination with the revolving brush D³, deriving its support from the counter-shaft D, and whereby it is free to hang downward under the influence of its own gravity, except when lifted by the rotation of the stud c' on the ratchet-wheel c, substantially as and for the purpose described.

EDWARD WESTON.
